UNITED STATES PATENT OFFICE.

JOSEPH LE VERNE TEACH, OF CHICAGO, ILLINOIS.

CLEANING COMPOSITION.

No Drawing.

Application filed July 5, 1924. Serial No. 724,447.

My invention relates to improvements in cleaning compositions, and it consists in the combination of ingredients hereinafter set forth and the steps taken in making the same.

5 An object of my invention is to provide a liquid in the nature of a cream which may be used without additional water, and which is primarily designed for cleaning the hands of grease, ink, paint, glue, dirt, etc.

10 A further object of my invention is to provide a cleaning compound of the type mentioned which does not have an injurious effect on the skin but which will leave the skin soft.

15 A further object of my invention is to provide a process of making a cleansing compound which produces a cleaner that may be thinned with water if desired, in other words, an emulsion which can be used in more or less concentrated state.

Other objects of my invention will appear in the following specification, and the novel features of the invention will be particularly pointed out in the appended claim.

25 In carrying out my invention I make use of kerosene, oleic acid, and aqueous ammonia. The following formula has been found to be very efficient: One hundred parts of kerosene by volume is mixed with thirteen

30 parts of commercial oleic acid. The oleic acid may be obtained either in light form or dark form, and either form will be equally effective in the compound. The mixture of kerosene and oleic acid is added to a mixture

35 of water and aqueous ammonia in the proportion of fifty parts by volume of water with three and one-half parts of 26% aqueous ammonia. This mixture is agitated, and when thoroughly mixed, it makes a thick,

40 white cream.

In order to get a liquid which is thin enough to shake and pour readily, I dilute the cream thus formed with water in the proportion of seventeen parts by volume of water and thirty-five parts by volume of 45 kerosene. The resulting mixture, as stated, is thin enough to shake and pour, but in itself forms a white cream of syrup-like consistency.

This cleansing compound thus formed will 50 remove almost all foreign matter from the hands, such as ink, paint, glue, grease, etc. It leaves the hands in a soft condition as distinguished from many hand soaps which contain strong alkalis. Furthermore, it is 55 an antiseptic compound and therefore tends to prevent infection by its antiseptic properties. The oleic acid has a triple function, it tends to form a body or base for the compound, it acts chemically to aid in dissolving 60 grease, etc., and it acts as a binder or agglutinant to form the emulsion of the kerosene and the water. The kerosene dissolves substances such as paint, gums, varnish, etc., which are not dissolved by water, and the 65 mixture of the three main ingredients provides, as stated, a cleansing compound which will remove almost any foreign substance which will ordinarily cling to the skin.

I claim:

The herein described cleansing compound which consists of a white creamy emulsion of syrup-like consistency containing substantially one hundred parts of kerosene, thirteen parts oleic acid, fifty parts of water, and 75 three and one-half parts of 26% aqueous ammonia.

JOSEPH LE VERNE TEACH.
